United States Patent Office.

THOMAS MOORE, OF BROOKLYN, NEW YORK.

Letters Patent No. 100,785, dated March 15, 1870.

GOVERNOR FOR STEAM-ENGINES.

The Schedule referred to in these Letters Patent and making part of the same.

To all whom it may concern:

Be it known that I, THOMAS MOORE, of Brooklyn, in the county of Kings, and State of New York, have invented a new and useful Improvement in Centrifugal Governors; and I do hereby declare that the following is a full, clear, and exact description thereof, which will enable others skilled in the art to make and use the same, reference being had to the accompanying drawings, forming part of this specification.

This invention relates to a new and useful improvement for governors for regulating the speed of steam-engines, and for all purposes to which it is applicable, whereby the governor is rendered more sensitive than governors of ordinary construction; and

The invention consists in the manner of confining and operating the balls, and in the general construction, arrangement, and combination of parts, as hereinafter more fully described.

In the accompanying drawing—

Figure 1 represents a vertical section of the improved governor through the line *x x* of fig. 2.

Figure 2 is a plan view, looking from the line *y y* of fig. 1.

Similar letters of reference indicate corresponding parts.

A is a fly-wheel.

B is the cone-pulley, by means of which the governor is operated.

C is a yoke, slotted so as to admit bell-cranks D and E, which are pivoted thereto at the points F F.

G G represent arms of the fly-wheel, connecting the center H with the rim of the wheel.

The fly-wheel, the cone-pulley, the yoke, and the center, with the arms G G, are all cast in a single piece.

I I represent the balls, which are confined on rods J J, which rods are fastened to the rim and to the center H. The balls slide on these rods as they are expanded by centrifugal force. The balls are made in two parts, screwed together, as seen in fig. 1.

K K represent springs, which pass through the center of the balls, as seen in the drawing.

The ends of these springs are confined in an interior groove, L, in the rim of the wheel A, plainly seen in fig. 1, and indicated by a dotted line in fig. 2.

The ends of the springs are curved and turned, so that they will readily move in the groove when the tendency of the balls is to straighten them by sliding outward in obedience to centrifugal motion.

m m represent slotted ears on each of the inner hemispheres of the balls, which connect with the arms of the bell-cranks D. The slots in the ears m allow the outward movement of the balls and the throw or necessary sweep of the arms of the cranks.

The pins, by which the arms are connected with the

ears, may be provided with friction rolls to render the movement more free than it would be with simple pins.

N represents the valve-rod, upon the lower end of which is the valve in the steam-pipe O.

P is a clasp on the top of the valve-rod, which is connected with the other arm of the bell-cranks D by the rods R R.

A screw-thread is cut on the upper portion of the valve-rod N.

S S represent screw-nuts on the valve-rod above and below the clasp P, by which the position of the valve is regulated.

The valve-rod plays freely through the center H of the governor, and the valve T, when properly adjusted to a given speed by means of the nuts S S, is varied in position by the movement of the balls according as the speed is increased or diminished.

The springs K K operate upon the balls unceasingly and render them extremely sensitive to any variation in the speed of the engine.

Although this governor operates upon the valve by means of centrifugal force, it may be placed in any position with the wheel A, either vertical, horizontal, or inclined. Its action is perfect in all positions.

The main parts of the governor being cast in a single piece, the cost of fitting up is comparatively small. They can consequently be furnished to the public at a reduced rate.

I am aware that divided balls confining springs between the two parts, the object of said springs being to return the balls to their normal position in opposition to the centrifugal force that may be brought to bear on the balls, have been before used. I do not, therefore, broadly claim such balls, as my invention relates to the mode of joining the parts of such balls, and the mode of confining and operating such springs.

Having thus described my invention,

I claim as new, and desire to secure by Letters Patent—

1. The independent springs K K and balls I I, the latter sliding upon the rods J J of the fly-wheel, in combination with slotted ears m m, bell-crank levers D D, and straps R R, all arranged and operated as set forth.

2. The spherical ball formed in two parts, one with a threaded shank, and the other with a correspondingly threaded recess, in combination with a spring, K, clamped between the said parts in the manner described.

THOS. MOORE.
